ATTORNEY

UNITED STATES PATENT OFFICE.

WILLIAM L. MORROW, OF STOCKTON, CALIFORNIA.

NUT-LOCK.

SPECIFICATION forming part of Letters Patent No. 788,324, dated April 25, 1905.

Application filed March 17, 1904. Serial No. 198,546.

To all whom it may concern:

Be it known that I, WILLIAM L. MORROW, a citizen of the United States, residing at Stockton, in the county of San Joaquin and State 5 of California, have invented certain new and useful Improvements in Nut-Locks, of which the following is a specification.

This invention relates to improvements in nut-locks, the object of the invention being to 10 provide a cheap and simple form of nut-lock by which the nut shall be effectually prevented from unscrewing from the bolt.

In the accompanying drawings, Figure 1 is a plan view of a bolt having the nut and jam-nut thereon constructed in accordance with 15 the invention. Fig. 2 is a longitudinal section of the same. Fig. 3 is an end view of the same. Fig. 4 is an end view, the jam-nut having been removed. Fig. 5 is a perspective 20 view of the main nut detached. Fig. 6 is a perspective view of the jam-nut detached. Fig. 7 is a similar view of a modified form of jam-nut. Fig. 8 is a perspective view of the key detached.

25 Referring to the drawings, 1 represents a bolt, 2 the main nut thereon, and 3 a jam or locking nut thereon. The bolt has in its threaded portion a longitudinal groove 4, in which is a key 5. The outer face of the main 30 nut 2 has a circular depressed portion 6, and in said depressed portion are again sunk a number of radial sockets or grooves 7, the sides of each groove being parallel. After the main nut has been screwed on into place a key 5 is 35 placed in the longitudinal groove on the outside of the nut, the upturned head 9 of the key being pushed into one of the radial sockets which has been brought into the same radial plane as the longitudinal groove. A jam- 40 nut 3 is now screwed onto the end of the bolt, the inner portion of said jam-nut entering the depressed circular portion of the main nut. In the modification of the jam-nut shown in Fig. 7 said jam-nut has an inner circular portion which fits closely within the circular depression 6 in the main nut, entirely covering 45 the same. In the modification of the jam-nut shown in Fig. 6 this circular portion is omitted. The outer surface of the jam-nut is 50 formed with a series of radial grooves 11 between abutments 12. After the jam-nut has

been screwed on so that one of these grooves is in the plane of the key the end of the key is turned up and forced into said groove 11. By this construction the following advantages are 55 obtained: The key is put in place after the nut has been screwed on, which is of great convenience, the inner portion of the key between the two nuts is entirely covered from the weather, the key is absolutely prevented 60 from slipping longitudinally outward in the groove, which would bring its head out of the socket in the main nut, and the two nuts are both absolutely locked in place against any outward movement. Not only are they locked 65 against outward movement, but also against creeping or inward movement, thus rendering the nut valuable on shafting and eccentrics where a definite amount of play is desirable. 70

I claim—

1. The combination of a bolt having a longitudinal groove in its threaded portion, a main nut having a series of radial key-sockets, a key in said groove with a head in one of 75 said sockets, a jam-nut engaged and locked by the outer end of said key, and a cover inclosing the outer ends of said key-sockets, as set forth.

2. The combination of a bolt having a longitudinal groove in its threaded portion, a main nut having a series of radial key-sockets, a key in said groove with a head in one of 80 said sockets, a jam-nut engaged and locked by the outer end of said key, and a cover carried 85 by said main nut and inclosing the outer ends of said key-sockets, as set forth.

3. The combination of a bolt having a longitudinal groove in its threaded portion, a main nut having a series of radial key-sockets, a key in said groove with a head in one of 90 said sockets, a jam-nut engaged and locked by the outer end of said key, and an annular flange extending from said main nut over the outer ends of said key-sockets, as set forth. 95

In witness whereof I have hereunto set my hand in the presence of two subscribing witnesses.

WILLIAM L. MORROW.
